(57) **CLAIM**

The ornamental design for an automobile entrance hatch, as shown and described.

DESCRIPTION

FIG. 1 is a front, top perspective view of an automobile entrance hatch, in a closed configuration, showing the new design;

FIG. 2 is a front elevational view thereof;

FIG. 3 is a right side elevational view thereof;

FIG. 4 is a top plan view thereof;

FIG. 5 is a front, top perspective view thereof, shown in an open configuration of use;

FIG. 6 is a front elevational view thereof;

FIG. 7 is a right side elevational view thereof; and,

FIG. 8 is a top view thereof.

The broken lines in the drawings illustrate portions of the automobile that form no part of the claimed design.
